RAZOR BLADE KNIFE

Leopold Karl Kuhnl, Stratford, Conn., assignor to Ever-sharp, Inc., New York, N.Y., a corporation of Delaware

Application October 24, 1957, Serial No. 692,213

5 Claims. (Cl. 30—156)

This invention relates generally to a pocket knife, and particularly to a pocket knife utilizing a standard razor blade for the cutting edge.

It is the general object of the invention to provide a new and improved razor blade pocket knife which is of relatively simple yet sturdy construction, which is very economical to produce, which may be safely handled and carried in a pocket, which has improved means for retaining the razor blade in a blade holder, and which has improved means facilitating opening of the knife.

Another object of the invention is to provide such a knife wherein the razor blade providing the cutting edge may very easily be replaced when old or broken without the use of tools, and wherein the blade when assembled in the knife will not become loosened or detached while in use.

A more detailed object of the invention is to provide a new and improved razor blade pocket knife including a handle having a vertical slot, a blade holder having a U-shaped cross section pivotably mounted at one end of the holder and pivotable between an open, operable position and a closed, carrying position in the slot, a blade carrier adapted to support a razor blade and pivotably mounted in the handle coaxially with the holder and pivotable with a razor blade supported thereon into the holder, the cutting edge of the blade projecting out of the holder, and means associated with the pivoted end of the carrier to provide a frictional spring action adapted to retain the carrier and the blade in the holder.

Another object of the invention is to provide such a knife wherein the handle is provided with a notch extending transversely of the slot and to a depth below the inverted edges of the U-shaped holder when the holder is in its closed position in the slot whereby the edges of the U-shaped holder provide abutments engageable by a person's fingernails to facilitate opening of the knife.

These and other objects and advantages of the invention will be apparent from a consideration of the razor blade knife structure which is shown by way of illustration in the accompanying drawings wherein:

Fig. 1 is a side elevational view of a preferred embodiment of the invention with the cutting blade in a closed position;

Fig. 2 is a top plan view of the knife as shown in Fig. 1;

Fig. 3 is a side elevational view of the blade carrier;

Fig. 4 is a top plan view of the blade carrier;

Fig. 5 is a side elevational view of the knife shown in Fig. 1 with the cutting blade in an open position;

Fig. 6 is a top plan view of Fig. 5;

Fig. 7 is a fragmentary side elevational view showing the blade holder in an open position and partially in vertical section, the blade carrier pivoted out of the blade holder, and a standard razor blade in broken lines supported on the blade carrier;

Fig. 8 is an enlarged vertical sectional view taken generally along line 8—8 of Fig. 1;

Fig. 9 is an enlarged vertical sectional view taken generally along line 9—9 of Fig. 5;

Fig. 10 is an enlarged vertical sectional view taken generally along line 10—10 of Fig. 7; and

Fig. 11 is an enlarged horizontal sectional view taken generally along line 11—11 of Fig. 5.

2

As shown in the drawings, an embodiment of the invention disclosed herein includes a knife body or handle portion 15 having an opening 16 formed in one end for hanging the knife on a nail, hook, key chain or the like. The handle 15, which may be formed of plastic or any other suitable material, has a vertical slot 17 formed therein extending from the opposite end of the handle 15 from the opening 16 substantially the length of the handle 15 and for substantially the entire depth thereof.

As best shown in Fig. 11, a tubular eyelet or bearing rivet 18 is secured in the slotted end of the handle 15 so as to extend transversely through the slot 17. A blade holder 20 has one end pivotably mounted on the bearing rivet 18 and is movable between an open, operable position, shown in Figs. 5, 6, and 7 and a closed, carrying position, shown in Figs. 1 and 2. As best shown in Fig. 9, the blade holder 20 has a U-shaped cross-sectional configuration which is inverted when the holder is in its closed position, as in Fig. 8.

A blade carrier 22, Fig. 3, adapted to support a razor blade of the standard injector type is pivotably mounted on the bearing rivet 18 coaxially with the blade holder 20 and disposed between the two spaced portions of the U-shaped blade holder 20. As best indicated in Fig. 7, the blade carrier 22 has an identical contour or elevational profile as the blade holder 20, including raised shoulders 24 and 21, respectively, adjacent the pivoted ends thereof, whereby it may be pivoted wholly within the blade holder 20. A slight variation between the contours of the blade holder 20 and the blade carrier 22 is provided, as shown in Figs. 5 and 6, with the free end or nose 28 of the blade carrier 22 extending slightly beyond the free end or nose 29 of the blade holder 20 to provide means for pivoting the carrier 22 out of the holder 20, particularly when a razor blade is not disposed on the carrier 22. The blade carrier 22 is provided with means for supporting a razor blade 23 for movement into the blade holder 20 in the form of a pair of punched-out projections or lugs 25 adapted to fit in a pair of holes usually found in a standard razor blade of this type. The blade 23 is thus supported against the side of the carrier 22 with the cutting edge 26 projecting from the upper edge of the carrier 22 and with the lower edge of the blade 23 being flush with the lower edge of the carrier 22, Fig. 10, for most effective blade support when positioned in the blade holder 20. As indicated in Fig. 10, the lugs 25 do not project beyond the outer surface of the blade 23.

In assembling a razor blade in the knife, the blade 23 is first positioned against the open blade carrier 22 with the projecting lugs 25 on the carrier 22 fitted in the holes in the blade 23 and then the carrier and blade are pivoted into the holder 20. As the inner end of the blade 23 does not extend as far as the shoulder 24 of the blade carrier 22, it is a very simple and safe procedure to press down on the shoulder 24 of the blade carrier 22 until it is flush with the corresponding shoulder 21 of the blade holder 20. As indicated in Figs. 5 and 9, the cutting edge 26 of the razor blade 23 when assembled in the blade holder 20 projects outwardly therefrom to provide a readily usable cutting edge.

In order to provide means for retaining the carrier 22 and the blade 23 in the holder 20, the end of the carrier 22 pivotably mounted on the bearing rivet 18 is bent out of the normal plane of the carrier 22, as best shown in Figs. 4 and 11, to provide a frictional spring action between the carrier and the holder. This bent configuration of the end of the carrier 22 also acts on the spaced portions of the blade holder 20 to provide a frictional spring action between the holder 20 and the handle 15.

In many pocket knives wherein the blade must be

opened from a closed position in a slot in the handle, it is necessary to provide a fingernail engaging groove in the blade. The construction disclosed herein provides means for opening the blade without the necessity of providing such a groove including a curved notch 30 formed in the upper surface of the handle 15 and extending transversely thereof and through the slot 17. The depth of the notch 30 is such that it extends below the inverted edges 32 of the U-shaped holder 20 when in its closed position with the edges 32 thus providing abutments engageable by a person's fingernails to facilitate opening the knife, as shown in Figs. 1 and 8.

The particular pocket knife structure disclosed herein is of the type having a razor blade cutting edge removably carried in a blade holder and includes improved means for retaining the blade in the blade holder and improved means facilitating opening of the knife from a closed position.

While I have shown and described a preferred embodiment of my invention, it is to be understood that it is capable of many modifications. Changes, therefore, in the construction and arrangement may be made without departing from the spirit and scope of the invention as disclosed in the appended claims.

I claim:

1. A razor blade pocket knife comprising, a handle having a vertical slot formed therein, a blade holder pivotably mounted at one end of said handle for movement between an open position and a closed position within said slot, said holder having a U-shaped cross section inverted when in said closed position, a blade carrier pivotably mounted at said one end of said handle coaxial with said holder and pivotable relative to said holder and in the plane thereof to a position within said holder, means on said carrier adapted to support a razor blade whereupon said carrier and the blade are adapted to be pivoted into the holder with the cutting edge of the blade projecting therefrom, and means defining a notch formed in said handle extending transversely through said slot and extending in depth beyond the inverted edges of said U-shaped blade holder when in said closed position in said slot whereupon said edges where the blade projects from the holder act as abutments engageable by a person's fingernails to facilitate opening of the knife.

2. A razor blade pocket knife comprising, a handle having a vertical slot formed therein, a blade holder pivotably mounted at said one end of said handle coaxial between an open position and a closed position within said slot, said holder having a U-shaped cross section inverted when in said closed position, a blade carrier pivotably mounted at said one end of said handle coaxial with said holder and pivotable relative to said holder and in the plane thereof to a position within said holder, means on said carrier adapted to support a razor blade whereupon said carrier and the blade are adapted to be pivoted into the holder with the cutting edge of the blade projecting therefrom, and means adapted to retain the carrier and the blade within the holder, said means comprising a bent configuration at the pivoted end of the carrier out of the normal plane of the carrier providing a frictional spring action between said carrier and said holder.

3. A razor blade pocket knife comprising, a handle having a vertical, longitudinally extending slot formed therein, a notch formed in the upper surface of one end of said handle and extending transversely through said slot, a blade holder pivotably mounted at the other end of said handle for movement between an open, operable position and a closed, carrying position in said slot, said holder being U-shape in cross section, a flat blade carrier member pivotably mounted coaxially with said holder for movement into said U-shape holder, a razor blade, means mounting the blade against one side of said carrier member with a cutting edge thereof extending beyond said carrier member said carrier being pivotable relative to

said holder and in the plane thereof, and means at the pivoted end of said carrier member providing a frictional spring action adapted to retain the carrier and the blade mounted thereon in said holder, said notch in said handle extending in depth beyond the inverted edges of said U-shape holder when in said closed position so that said edges provide abutments engageable by a person's fingernails to facilitate opening the knife.

4. A razor blade pocket knife comprising, an elongated handle member having a vertical slot formed therein intermediate the sides of said member and extending from one end of said handle member substantially to the other end thereof, a bearing rivet secured in said one end of said handle member and extending through said slot, a

blade holder having one end journaled on said rivet and adapted to be pivoted between an open position extending from said one end of said handle member and a closed position substantially within said slot, said holder having a U-shaped cross section inverted when in said closed position, a blade carrier having an identical elevational profile as said holder and having one end journaled on said bearing rivet intermediate the spaced portions of said U-shaped blade holder, said carrier being pivotable relative to said holder and in the plane thereof to a position

wholly within said U-shaped blade holder, a standard injector type razor blade having at least two openings spaced along the length thereof, at least two projecting lugs spaced along the length of said carrier and fitted in said openings formed along the length of said razor blade whereupon said blade is mounted against said carrier and is pivotable therewith into said U-shaped blade holder, the widths of said carrier and said holder being such that the cutting edge of the razor blade extends beyond the open edges of said U-shaped blade holder, the end of said carrier journaled on said bearing rivet being bent out of the normal plane of the carrier to provide a frictional spring action adapted to retain the carrier and the blade within said holder, and means defining a transverse notch in the upper surface of the handle member at

the opposite end of the slot from said bearing rivet and extending through said slot, said notch having a depth extending below the open edges of said U-shaped blade holder when pivoted into its closed position in said slot whereupon said open edges act as abutments engageable by a person's fingernails to facilitate opening of the knife.

5. A razor blade pocket knife comprising, a handle having a vertical slot formed therein, a blade holder pivotably mounted at one end of said handle for movement between an open position and a closed position within said slot, said holder having a U-shaped cross section inverted when in said closed position, a blade carrier pivotably mounted at said one end of said handle coaxial with said holder and pivotable relative to said holder and in the plane thereof to a position within said holder, said holder and said carrier having identical elevational contours, means on said carrier for supporting a razor blade in spaced relationship from the pivoted end of said carrier whereupon said carrier and the blade are adapted to be safely pivoted into the holder with the cutting edge of the blade projecting therefrom by merely pushing on the edge of the carrier adjacent the pivoted end thereof until said edge is flush with the corresponding edges of the holder, and means adapted to retain the carrier and the blade within the holder, said means comprising a bent configuration at the pivoted end of the carrier out of the normal plane of the carrier providing a frictional spring action between said carrier and said holder.

UNITED STATES PATENT OFFICE
CERTIFICATE OF CORRECTION

Patent No. 2,914,850

December 1, 1959

Leopold Karl Kuhnle

It is hereby certified that error appears in the printed specification of the above numbered patent requiring correction and that the said Letters Patent should read as corrected below.

Column 3, line 47, strike out "said", first occurrence; same line, for "coaxial" read -- for movement --.

Signed and sealed this 28th day of June 1960.

(SEAL)

Attest:

KARL H. AXLINE

Attesting Officer

ROBERT C. WATSON
Commissioner of Patents
